Primary Examiner — Derrick E Holland*Assistant Examiner* — Jennifer O King(74) *Attorney, Agent, or Firm* — Hammer & Associates, P.C.(57) **CLAIM**

The ornamental design for a battery separator, as shown and described.

DESCRIPTION

FIG. 1 is a perspective view of a battery separator showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets(56)
